UNITED STATES PATENT OFFICE.

MAX C. MILLER, OF CUMBERLAND HILL, RHODE ISLAND, ASSIGNOR TO JEROME FLEISCHER, OF PROVIDENCE, RHODE ISLAND.

CUFF BUTTON.

Application filed November 10, 1919. Serial No. 336,881.

To all whom it may concern:

Be it known that I, MAX C. MILLER, a citizen of Germany, and resident of the town of Cumberland Hill, in the county of Providence and State of Rhode Island, have invented certain new and useful Improvements in Cuff Buttons, of which the following is a specification.

This invention relates to cuff buttons of the class constructed of two members detachably connected together; and the object of this invention is to provide such a cuff button having means for positively locking the two members of the button together when the stud-portion of one member is inserted into the socket portion of the other member and rotated a portion of a revolution by which construction the parts may be readily connected and cannot be accidentally separated as is the case with some constructions of separable buttons.

With these and other objects in view, the invention consists of certain novel features of construction, as will be more fully described, and particularly pointed out in the appended claims.

In the accompanying drawings:

Figure 1 is a side elevation of my improved button, showing the two parts as connected together.

Figure 2 is a side elevation of the button, taken at a right angle to the position illustrated in Figure 1.

Figure 3 is a plan view sectioned on line 3-3 of Figure 1, showing the cross-bar of the stud-member as engaging the slanting side walls of the spring to depress the same sufficiently to pass over the top of the spring into the retaining medial transverse depressions in the spring arms.

Figure 4 is a perspective view of one form of cross bar retaining spring.

Figure 5 is a face view of the base-plate of the socket portion.

Figure 6 is a top view of the socket cap, showing the slot therein.

Figure 7 is a perspective view showing the cross bar on the end of the stud member.

Figure 8 is a modified form of flat spring for retaining the lock-bar in connected position.

With reference to the drawings, the stud member of my improved button comprises a shank 10 having a head 11 at one end and a cross bar 12 at its opposite end and the

socket member of this button is also provided with a shank 13 having a head 14 at one end and a plate 15 at its opposite end. This plate is substantially circular in form, as illustrated in Figure 5, and is notched at 16 on its opposite edges for the reception of 60 the spring presently described.

On this plate I mount a cap 18 whose outer wall is slotted as at 24 to permit the passage of the cross bar 12 and the body of this cap is preferably provided with an inwardly-extending, annular rib 19 engaging the upper face of the plate 15 and the lower edge 20 of this cap is rolled over the edge of the plate 15, said roll being of sufficient depth to cover the cut-out or notched portions 16 of 70 this plate.

Within this cap I mount a compression spring which may be constructed in frame form, the side walls 21 of which are spaced apart and set on an angle, the base-portion 22 being turned outwardly to rest upon and slide on the plate 15 while the ends of this frame are turned downwardly as at 23 to extend into the slots 16 in this plate to hold this spring against lateral displacement 75 when the cross bar engages the same with 80 its necessary rotating action.

The middle portions of the spring arms are bent or depressed as at 25 forming a transverse socket groove into which the cross bar is adapted to snap and fit to retain it in 85 locked position when rotated one-quarter turn after having passed through the receiving slot in the cap.

I do not wish to be restricted to this particular form of spring as in some cases instead of forming the spring of wire having spaced apart side arms, I may form the same of a flat strip of resilient metal as illustrated in Figure 8, which is adapted to perform all of the functions of a spring made of wire. 95

I claim:

1. A separable cuff button comprising a stud member, a socket member, and a spring held against relative rotation in said socket member and provided with a recess for receiving and releasably engaging the stud end of the opposite member when said stud is passed into the socket and rotated a portion of a revolution. 100

2. A separable cuff button comprising a 105 stud-member having a head at one end and a cross bar at the opposite end, a socket member having a head at one end, and a notched

plate at its opposite end, a slotted cap on said plate to receive said cross bar and a spring in said socket having its ends turned down into said notches in said plate 5 and arranged to act upon and releasably retain said cross bar in said socket when forced therein against its pressure and rotated a portion of a revolution.

3. A separable cuff button comprising a 10 stud-member having a head at one end and a cross bar at its opposite end, a socket member having a post with a head at one end

and a plate at its opposite end, a cap member having its edge rolled over that of said plate, the outer wall of said cap being provided with a slot, and a compression spring retained within said cap arranged to act upon and releasably retain the cross bar of said opposite member within said cap when passed through said slot and rotated a portion of a revolution within said cap. 15 20

In testimony whereof I affix my signature.

MAX C. MILLER.
